UNITED STATES PATENT OFFICE.

THOMAS H. SEELEY, OF DORCHESTER, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,161,894.

Specification of Letters Patent. Patented Nov. 30, 1915.

Application filed August 24, 1912. Serial No. 716,898.

To all whom it may concern:

Be it known that I, THOMAS H. SEELEY, a citizen of the United States, and resident of Dorchester, county of Suffolk and State of Massachusetts, have invented an Improvement in Work-Supports, of which the following description, in connection with the accompanying drawings, is a specification, like letters on the drawings representing like parts.

The invention to be hereinafter described relates to shoe supports, and more particularly to that type for sustaining a shoe during the action of a tool and while on the last.

As well known by those skilled in the art, shoe lasts are formed with a last pin receiving recess which is designed to receive the last pin of a jack or shoe support, and when the shoe is jacked to effect its steady support during the action of a tool thereon the last is held between the last pin and another element, such as a toe or other rest. In order to jack the shoe, relative movement is imparted to the last pin and toe or other rest, and to this end the last pin may be mounted to tilt about a pivotal mounting in order to throw the toe portion of the shoe upon the toe or other rest. This tilting action of the last pin is preferably transmitted through a yielding element, so that the last may not be broken or injury done the shoe. The last pin sockets in lasts, however, are not always uniformly located, but vary in different lasts and even in lasts of the same size, not only in position but also in their inclination with reference to the top or crown of lasts, so that tilting action of the last pin that will be sufficient to properly jack the shoe in one case would be unsuitable in another case, and, where the jacking action is transmitted through a yielding element, such for instance as pointed out in the patent to Plant, No. 958,283, the effective tension of the yielding element will so far vary that it may be too great in some cases and too little in others.

With these general facts in mind the aims and purposes of the present invention are to provide means whereby the shoe may be jacked with uniform pressure upon the toe or other rest, regardless of variations in the position or inclination of the last pin sockets, all as will hereinafter more fully appear from the following description and accom-

panying drawing of one form of means for carrying the invention into practical effect, it being understood that in its true scope the invention is defined by the claims.

In the drawings:—Figure 1 is a side elevation, partly in section, of a jack or shoe support embodying a convenient and practical form of the invention; and Fig. 2 is a detached detail in longitudinal section of the jacking slide and associated parts.

As a convenient illustrative form of the invention, the drawings illustrate the general character of jack or shoe support shown and described in the Plant Patent No. 958,283, May 17, 1910, and reference may be made thereto for a detail disclosure of those features of the jack or shoe support not essential to the present invention and the general manner of operation, it being understood that the invention itself is not restricted thereto, but is applicable to other forms of jacks or shoe supports.

Rising from the main portion of the jack 1, is a post 2, and pivotally mounted at 3 on the post 2 is the last pin support 4 having the last pin 5, the lower end of said last pin support 4 being connected at 6 to an upwardly projecting arm 7 rising from an actuating link or slide 8, said link or slide 8 being preferably formed as a yielding member, and as shown in the present form of the invention comprising two parts 9 and 10, connected by an adjusting bolt or rod 11, in a manner that will presently appear, the construction being such that upon movement of the link or slide 8 to the left, Fig. 1, the last pin support will be turned with a yielding movement to jack the shoe.

Pivotedly mounted at 12 on the jack proper is the jacking lever 13, having a crank arm 14 connected by a link 15 to an eccentric shaft 16, for operating the jack lock, all substantially as fully described in the said Plant patent, to which reference may be had, but as these locking details form no essential part of the present invention and may be as set forth by said patent or otherwise, the particulars thereof are not here shown.

The toe rest 17 is preferably mounted for adjustment on the carrier 18 secured to a toe rest support 19 pivotally mounted upon the jack at 20, and these parts and their operative relation may be the same as fully described in the said Plant patent, or of any

desired character, the essential in this respect being that the jack be provided with some kind of a toe rest or other support to receive and sustain the toe portion of the shoe when the latter is jacked.

As hereinbefore stated, the link or jacking slide 8 is preferably formed of the two relatively adjustable parts 9 and 10, and threaded within the part 9 is an adjusting sleeve 21 through which loosely extends the rod 11 having a thread connection at 22 to the part 10 of said slide, the outer end of said rod 11 being provided with the lock nuts 23 bearing against the outer end portion of the adjusting sleeve 21.

Mounted on the rod 11 between a loose collar 24 and the part 10 of the slide is a spring 25 normally holding the parts 9 and 10 of the slide in separated relation, and the adjusting sleeve 21 is provided with a capstan head 26 whereby it may be rotated for adjusting the two parts of the slide relatively to each other, the construction being such that by rotation of the adjusting sleeve 21 between the nuts 23 and collar 24, the two parts 9 and 10 of the slide may be adjusted toward or from each other to thereby vary the length of the slide without at the same time varying or disturbing the jacking tension of the jacking spring 25, and conversely by proper manipulation of the nuts 23 and the adjusting sleeve 21 the jacking tension of the jacking spring 25 may be varied to suit conditions of use without varying the length of the jacking slide.

The arm 7 connected to the last pin support 4 is secured to or formed as part of the part 9 of the jacking slide, consequently variation in the length of the jacking slide by manipulation of the adjusting sleeve 21 will vary the initial inclined position of the last pin 5 to suit the varying inclination of last pin sockets in different lasts without at the same time disturbing the jacking tension of the jacking spring, with the result that regardless of such variation in the last pin sockets of different lasts, uniform jacking of shoes may be secured.

Rising from the part 10 of the jacking slide 8 is a lug or projection 27 having a slot 28 which is engaged by a pin or projection 29 carried by the jacking lever 13, whereby upon movement of the jacking lever contra-clockwise, Fig. 1, movement will be imparted to the jacking slide and through the spring 25 the shoe will be yieldingly jacked.

While the particular devices herein shown and described present a practical and convenient form of the invention and enable shoes to be uniformly and yieldingly jacked regardless of the different positions or inclinations of the last pin sockets in different lasts, it is to be understood that the invention is subject to modification in details and

structure and is not limited to such as are herein presented for the purpose of exploitation, and while the jack is peculiarly adapted for the support of shoes during the laying and leveling operation, it and the invention may be otherwise employed and in other relations.

What is claimed is:—

1. In a shoe support, the combination of a last pin to engage the last pin socket of a last, a toe rest, and means for relatively moving the last pin and toe rest to fully jack the shoe with a yielding pressure, said means being constructed and arranged to permit the same predetermined yielding jacking pressure to be maintained throughout a series of shoes, the lasts of which have pin sockets of different inclination.

2. In a shoe support, the combination of a last pin to engage the last pin socket of a last, a toe rest, yieldingly acting means to seat the toe of the shoe with yielding pressure upon the toe rest as the shoe is jacked, and means to alter the relations of parts of said yieldingly acting means to effect the same predetermined yielding pressure of shoes upon the toe rest regardless of different inclinations of last pin sockets.

3. In a shoe support, the combination of a pivotally mounted last pin to engage the last pin sockets of lasts, a rest to sustain the forepart of a shoe while on the last, a jacking lever, and yielding means between the jacking lever and last pin for tilting the last pin to seat the forepart of the shoe yieldingly upon said rest as the shoe is jacked, said means including an adjustment enabling the last pin to be tilted different amounts by movement of the jacking lever while still maintaining the same yielding character of said means to secure the same predetermined yielding pressure of the forepart upon the rest by lasts having pin sockets of different inclinations.

4. In a shoe support, the combination of a tilting last pin to engage the last pin socket of lasts, a rest for the forepart of a shoe while on the last, means for yieldingly tilting the last pin through a path to seat the forepart of the shoe on said rest, and means to change the path of tilting movement of the last pin to suit lasts having last pin sockets of different inclinations and maintain the same yielding action of the last pin in its different paths of tilting movement.

5. In a shoe support, the combination of a tilting last pin to engage last pin sockets of lasts, a rest for the forepart of a last, jacking means for yieldingly tilting the last pin to seat the forepart of a last upon said rest with a predetermined yielding pressure, and means for adjusting the initial position of the last pin with relation to the jacking means to suit different inclinations of last

pin sockets while maintaining the same yielding action of the last pin to enable the predetermined yielding pressure to be maintained for all lasts.

- 5 6. In a shoe support, the combination of a tilting last pin to engage the last pin sockets of lasts, a rest for the forepart of a shoe on the last, a jacking lever, a link or slide connecting the jacking lever operatively .0 with the tilting last pin, said link comprising relatively yielding portions, and means for adjusting the length of the link while maintaining the same yielding relation between the portions thereof.
- 15 7. In a shoe support, the combination of a tilting last pin, a toe rest, jacking means for tilting the last pin including a spring, pressure-transmitting connections acting through said spring, and means for changing the length of the connections while maintaining the same spring action.

- 20 8. In a shoe support, the combination of a tilting last pin, a toe rest, jacking means for tilting the last pin including a two-part link or slide, a spring for transmitting power from one to the other part of said link or slide, and means for relatively ad-

justing the two parts of the link or slide while maintaining the transmitting power of the spring unchanged.

9. In a shoe support, the combination of a tilting last pin, a toe rest, jacking means for tilting the last pin to jack the shoe including a pressure-transmitting spring, and means for changing the path of tilting movement of the last pin while maintaining the pressure-transmitting action of the spring unchanged.

10. In a shoe support, a tilting last pin, a jacking lever for tilting the last pin to jack the shoe, a link or slide between the jacking lever and last pin including the two members 9 and 10, a jacking spring 25 between said members, a rod 11 connecting said members, and a part 21 for relatively adjusting said members independent of spring adjustment.

In testimony whereof, I have signed my name to this specification, in the presence of two subscribing witnesses.

THOMAS H. SEELEY.
